United States Patent Office

Des. 227,446
Patented June 26, 1973

227,446

HOLDER FOR A RAZOR AND A BLADE DISPENSER

Martin Glaberson, Ardsley, N.Y., assignor to Warner-
Lambert Company, Morris Plains, N.J.

Filed Apr. 17, 1972, Ser. No. 245,042

Term of patent 14 years

Int. Cl. D9—03

U.S. Cl. D9—186

FIG. 3

FIG. 4

FIG. 1 is a top perspective view of a holder for a razor and a blade dispenser showing my new design;

FIG. 2 is a top plan view;

FIG. 3 is a side elevational view, the opposite side being a mirror image of the side shown; and

FIG. 4 is a bottom plan view thereof.

I claim:

The ornamental design for a holder for a razor and a blade dispenser, as shown and described.
